WASHING MACHINE FOR SPINNING CAKES

Karl Meyer-Gaus, Wuppertal-Elberfeld, Germany, assignor to American Bemberg Corporation, New York, N. Y., a corporation of Delaware

Application August 5, 1930, Serial No. 473,259
In Germany August 5, 1929

2 Claims. (Cl. 18—8)

Most of the devices for washing spinning cakes according to the well known process permit of but a poor production, so that quite a considerable number of such expensive devices are required. Other devices, again, that permit of the treatment of cakes in large quantities, do not always give the desired results, as the cakes are not sufficiently penetrated by the fluids in question. For washing artificial silk in skein form, 10 mechanical devices have been brought out, having a frame with fixed cross-rod for the reception of cut skeins, the frame itself being arranged over a trough and fitted for being raised and lowered.

For artificial silk spinning bobbins, too, mechanical washing devices are known. The characteristic of these devices is that, the perforated spools are placed between two rotating discs, that are partially immersed in the bath, subjected to 15 vacuum and periodically submitted to the influence of the respective bath.

These devices are, however, more or less unsuited for spinning cakes; they are either troublesome of service and therefore costly, or the spinning cakes get tangled.

Finally, machines for the treatment of skeins have made their appearance, the yarn carriers of which, arranged on both sides, rotate outside the bath above the trough, drawing the skein at the same time through the bath. These machines, too, are but little suited for spinning cakes, as an immersion of the cakes into the bath on these machines is scarcely possible, the spinning cakes having but a small diameter.

The object of this invention is a machine, 35 which shall treat a large number of cakes at one and the same time, both quickly and efficiently. The device consists of a support on which frames are suspended by means of crank mechanism and hanging devices, the spinning cakes being hung on the frames by means of rods. The cakes may remain in this position 40 during the whole treatment, thus avoiding the disadvantages attendant on drawing the cake through the bath. On setting the crank mechanism in motion, the frame together with the spinning cakes is subjected to a circulating motion. The treatment is much more effective, if 45 the frame with the spinning cakes is lifted out of the bath on every rotation of the crank, and then immersed again; in this case, a slow revolution of the crank should be chosen, as then 50 the fluid is able to flow to a great extent out of the raised cakes, which take up a fresh quantity of the bath on being reimmersed.

55 The machine may be constructed in double

form, both sides of the carrier being fitted with crank mechanism and hanging devices to take the frames for the spinning cakes. It will be found expedient to set off the crank mechanism on both sides at 180°, in order to provide for a good balancing of the frames. Should only one trough be employed for the double-sided and offset arrangement of the crank mechanism for both frames, it will be found that, on carrying out the treatment by immersion, the further advantage of the bath being thoroughly stirred is obtained, as, on the immersion of each frame, the fluid is driven over to the side then free.

The spinning cakes may be placed on sticks on the frames, not laced and loose. It will, however, be found more effective to place them on holding devices, that are capable of expansion and the circumference of which may be varied, viz. on reels, to provide for a full effect of the fluid on the inner surface of the cake.

If, as is usually the case, several baths are required for the subsequent treatment, several troughs will be placed next to or behind one another; above the troughs there is a track on which the yarn sticks may be run by means of travelling cranes. This track may be endless, so that the yarn sticks may be conveniently brought back to the starting point.

The yarn sticks are brought into position on special stands at the end of the troughs, by means of pulley blocks.

The drive for the crank mechanism of the carrier may be on the carrier itself or may be firmly arranged on the support. In the first arrangement, a shaft, supplied with worms and running lengthwise to the yarn carrier, is driven by a motor at the end of the carrier. By means of worm-wheels on the shafts of the crank mechanism, these are rotated by the worms. The shaft with the worms, worm-wheels and the shafts of the crank mechanism may be carried oil-tight within the carrier, that is in the form of a pipe. This arrangement is of special advantage when the carrier is double-sided and only one common trough is employed, as then no impurities can fall into the bath.

The drawing represents one form of the machine for the sake of example. In the drawing

Fig. 1 is a side elevation with a longitudinal section of the trough,

Fig. 2 is a view from above,

Fig. 3 is a view of, the top-end of the trough, the carrier being raised,

Fig. 4 is the same view with the carrier lowered into position,

Fig. 5 is an enlarged detail view of the crank mechanism shown in Fig. 4.

At the ends of the trough *a* there are supports *b* with surfaces *c*. On these surfaces, a carrier *d* with crank mechanism *i* may be placed. On the crank mechanism the frames *m* are suspended by means of the hanging devices *l*. Threaded on sticks *n* small, adjustable reels *o*, capable of expansion, are placed on the frames *m*.

10 A shaft *f*, provided with worms, is turned by a motor *e*. This shaft gives the crank shaft *h* a slow rotation by means of the worm-wheels *g*. In this manner, the crank mechanism *i*, *k* also receive a rotary motion and raise and lower the frames *m* by means of the hanging devices *l*. In this way, spinning cakes *o* on the frames *m* are immersed in and lifted out of the bath again at regular intervals.

15 What I claim is:

20 1. A washing machine for artificial silk spinning cakes, comprising a trough, supports

adjacent said trough, a carrier supported on and adapted to be lifted off said supports, said carrier being tube-formed, gearing situated within said tube-formed carrier, a crank operatively connected with the gearing, a frame for carrying a plurality of spinning cakes, and means to hang the frame on the crank.

2. Apparatus of the character described for washing filament masses, comprising a bath, a tubular member extending above the bath, means to support the tubular member, a shaft in the tubular member having a worm secured thereto, a gear in the tubular member for rotation by the worm, a shaft extending through the sides of the tubular member and secured to the gear, crank arms in generally vertical planes secured to the last-named shaft on opposite sides of the tubular member, means for supporting a plurality of said filament masses, and means for hanging the last-named means on the crank arms.
